UNITED STATES PATENT OFFICE.

HERBERT L. CONGER, OF MILWAUKEE, WISCONSIN.

DESIGN FOR A BOOK-MARK.

SPECIFICATION forming part of Design No. 32,731, dated May 29, 1900.

Application filed May 5, 1900. Serial No. 15,650. Term of patent 7 years.

To all whom it may concern:

Be it known that I, HERBERT L. CONGER, a citizen of the United States, residing at Milwaukee, in the county of Milwaukee and State 5 of Wisconsin, have invented and produced a new and original Design for a Book-Mark; and I do hereby declare the following to be a full, clear, and exact description of the same, reference being had to the accompanying 10 drawings, forming a part thereof.

In the said drawings, Figure 1 represents a plan view, Fig. 2 a transverse sectional view on the line 2 2 of Fig. 1, and Fig. 3 a like sectional view on the line 3 3 of Fig. 1, of a 15 book-mark embodying my new design.

My design relates to the new and original shape or configuration of the article.

The leading or essential feature consists in the unitary design for a book-mark made the 20 subject of illustration, comprising the shape of the right-hand portion A of the article, (in the position shown in Fig. 1,) having a continuous straight upper edge its entire length, as shown, between the points marked *a* and *b*, 25 respectively, and a straight lower edge between the points *c* and *d*, the said lower edge being formed on the line of the arc of an ellipse between the points *d* and *e*, the extreme right-hand end being formed on a rounded line 30 between the points *e* and *b*, together with the shape of the left-hand portion B of the article, (in the position shown in said Fig. 1,) where it is formed on parallel straight lines, as shown, 35 between the points *f* and *g* and between the points *h* and *i*, with a rounded extreme left end, as shown, between the points *f* and *h*,

and the shape of the intermediate portion C of the article, following the lines of two inwardly-inclined opposite lines between the points *g* and *j* and between the points *i* and *k*, the said inclined lines being slightly concavely rounded as they approach the points *j* and *k*, respectively, and thence merging into oppositely-rounded convex lines between the points *j* and *l* and between the points *k* and *m* 45 and terminating in transverse short straight lines between the points *l* and *a* and between the points *m* and *c*.

Minor features of said design comprise forming the parts A and B of the same width 50 transversely from edge to edge, as best shown in the section views, Figs. 2 and 3, and the whole article of the same thickness, save that the entire edge of the part A, opposite to the edge between the points *a* and *b*, is converged 55 from each side to form a sharp edge, as best shown at *n* in Fig. 3, in contrast to the opposite square edge of the portion A between the points *a* and *b*, as best shown at *o* in said Fig. 3, both edges of the portion B having likewise 60 square edges, as best shown at *p* *q* in Fig. 2.

Having thus described my invention, what I claim as new, and desire to secure by Letters Patent, is—

The design for a book-mark, substantially 65 as herein shown and described.

In testimony whereof I affix my signature in presence of two witnesses.

HERBERT L. CONGER.
